[57] CLAIM

The ornamental design for a mascara shield, as shown and described.

DESCRIPTION

FIG. 1 is a perspective view showing the top, front and left sides of a mascara shield embodying my new design; FIG. 2 is a front elevational view thereof;

FIG. 3 is a top plan view thereof;

FIG. 4 is a rear elevational view thereof;

FIG. 5 is a bottom plan view thereof;

FIG. 6 is a left side elevational view thereof, the side opposite being a mirror image of the side shown;

FIG. 7 is a perspective view shown in use; and,

FIG. 8 is a further perspective view shown in use.

The broken line showing of the human eye is for illustrative purposes only and forms no part of the claimed design.

FIG. 1

FIG. 4
